UNITED STATES PATENT OFFICE.

HERBERT HORSFALL, OF BRIDGEPORT, CONNECTICUT, ASSIGNOR TO SALT'S TEXTILE MANUFACTURING COMPANY, OF BRIDGEPORT, CONNECTICUT, A CORPORATION OF CONNECTICUT.

DISPLAY STAND.

1,404,439.

Specification of Letters Patent. Patented Jan. 24, 1922.

Application filed April 5, 1920. Serial No. 371,192.

To all whom it may concern:

Be it known that I, HERBERT HORSFALL, a citizen of the United States, residing at Bridgeport, in the county of Fairfield, State 5 of Connecticut, have invented certain new and useful Improvements in Display Stands, of which the following is a specification.

This invention relates to an improved display-stand or easel for holding and displaying 10 textile goods or similar sheet materials in stores, salesrooms, and other mercantile establishments.

One object of the improvement is to provide a stand or easel on which fine materials 15 such as pluses, velvets, fur-effects and other pile-fabrics may be hung or suspended with their surfaces held apart and protected from contact to prevent marring or damaging the delicate finish of the goods.

Another object of the improvement is to provide a display-device or stand on which the goods may be compactly arranged to economize floor space, while permitting of 20 easy and convenient inspection for examination of their texture and finish.

A further object of the improvement is to provide a display-stand which is easily portable to move the goods to different positions for storage or display, and from which the 25 material may be conveniently unreeled or delivered in cutting it up for the trade.

Other objects of the improvement will appear from the detailed description of the invention contained in the following specification which is illustrated by the accompanying drawings. In the drawings:

Fig. 1, is a view illustrating one embodiment of my improved stand in side elevation, with its rotatable turntable and bearing 40 shown in section in an axial plane;

Fig. 2, an enlarged end view of the cloth-frame or support on which the goods are stretched or hung;

Fig. 3, a detailed view of one of the end-members of the cloth-support or frame, shown part sectional on the line X—X of 45 Fig. 2;

Fig. 4, a plan view of the base or pedestal of the stand, showing the turntable which 50 is rotatably mounted thereon;

Figs. 5, 6 and 7, enlarged detailed views of the clamping-means for fastening the cloth-frame to the turntable; and

Fig. 8, a view showing a modification in

the form of pedestal for the stand and in 55 the arrangement of the turntable bearing.

Referring to Fig. 1 of the drawings, in the present embodiment of the invention, my improved display-stand or easel comprises, essentially, a base or pedestal 2; a 60 revolving support or turntable 3 rotatably mounted on the pedestal; and a cloth-frame 4 supported on the turntable to revolve therewith.

The cloth-frame or holder 4 for the fabric 65 is preferably constructed with two opposite end-members or stretchers 5, fastened to the ends of a longitudinal stringer or board 6. The end-members 5 may be formed from flat strips of metal bent into Y-shaped loops 70 7, see Fig. 2, and having their connecting branches 8 bolted to the opposite sides of the board 6. The bolts 9 pass through slots 10 in the ends of the board 6 to provide for adjusting the members 5 toward and away 75 from each other to accommodate strips of fabric of different widths stretched between them. Riveted to the sides of the angular arms of the members or stretchers 5 are strips of metal formed with depending cloth- 80 hooks 11, see Fig. 3. The hooks 11 are adapted to be pierced through the selvages of the cloth C to stretch it between the members 5 when it is reeled onto the frame in the manner as shown in Fig. 2. In applying 85 the fabric to its frame or holder 4 the cloth is grasped at its marginal edges, drawn taut between the stretchers 4 and its selvages impaled on the hooks 11. Usually two operators stretch the piece of goods between 90 them, and starting at the inner hooks, as shown at 12, Fig. 2, revolve the frame 4 on suitable supports while progressively fastening the cloth to the successive hooks 11. The finished side of the goods, that is 95 to say, the pile surface on velvets, pluses and other pile-fabrics, is turned inwardly and the hooks 11 are spaced at a suitable distance apart to insure that the finished face of each length of fabric shall be separated 100 and maintained free from contact with the back of the adjacent underlying length of fabric. In this way the soft, delicate pile of the fabric is protected from being marred or injured, either from its own contact, or 105 from the handling of the goods in transit or while storing or displaying the same.

The base or pedestal of the stand may

be of any preferred form and structure and I have illustrated two different embodiments of this part of the device in the drawings. As shown in Figs. 1 and 4, the base 2 is constructed with a circular top-plate 15 provided with legs 16 projecting downwardly from its rim. Preferably, the legs 16 are mounted on rollers or casters 17 swiveled to their lower ends to provide for wheeling the stand along the floor on which it sets. Fastened to the center of the top-plate 15 is a circular bearing-member 18 formed with an annular ball-race 19 adjacent its outer edge.

As shown in Fig. 4 the turntable 3 comprises a flat plate 20 having a central bearing disk 21 fastened to its under side and adapted to overlie the bearing-member 18 on the base 2. The disk 21 is formed with a ball-race 22 adapted to receive a series of balls 23 held in the race 19 of the lower bearing-member 18. A shouldered stud 24 is riveted through the center of the disk 21 and projects down through an axial bore in the bearing 18 and plate 15, with its lower end reduced in diameter and threaded to receive a nut 25. The nut 25 is set up against a washer 26 abutting the shoulder on the stud 24 and bearing against the under side of the plate 15 to prevent the disk 18 from canting or lifting away from the balls in the lower race 19. The balls 23 take the downward thrust of the turntable 3 to support the weight of the cloth-frame 4 and the fabric carried thereon; and thus an anti-friction bearing is provided to adapt the frame to be revolved easily to unwind the cloth for displaying its finish, or for delivering it in lengths as required to be cut from the piece.

The turntable 3 may be circular in outline if desired, but preferably I construct it of skeleton form for the purpose of saving weight and economizing metal. As shown in Fig. 4 the turntable is of H-shape having end-pieces 26 connected by parallel cross-strips 27 fastened to the bearing disk 21 by screws 28. In the end-pieces 26 I form inclined slots 29 adapted to receive clamping-members 30 for fastening the cloth-frame 4 to the top of the turntable. The clamps 30 may consist of bolts 31 having hooks 32 at their upper ends adapted to hook over the arms 7 of the end-members 5 of the cloth-frame 4. The bolts 31 project downwardly through the slots 29 and are slideable longitudinally thereof to adapt them for adjustment to accommodate cloth-frames of different sizes. Threaded onto the lower ends of the bolts 31 are thumb-nuts 33 which are screwed against washers 34 abutting the under side of the turntable 3, thus acting to draw the hooks down against the end-members 5 to clamp the cloth-frame 4 in place.

Any other suitable means may be employed for clamping the cloth-frame to the top of the turntable 3, and in Figs. 6 and 7 I have illustrated an improved form of quick-acting clamp as next described. In this modification of the device the clamp-hooks 35 are provided with eyes or loops 36 at their lower ends adapted to receive pins 37 which act as pivots for finger-levers 38. The levers 38 are formed with double, eccentric cam-faces 39 arranged to bear against the under face of the turntable 3 at the sides of the slots 29. When the levers 38 are pressed upwardly, as shown in Fig. 6, their cam-faces 39 act as wedges to draw the hooks 35 down to bind against the end-members 5 of the frame 4; while to release the hooks from the frame-members it is only necessary to press downwardly on the levers to rotate their eccentric portions to loosen the hooks to free them from the frame.

Fig. 8 of the drawings illustrates a modified form of base or pedestal for the stand and a different type of bearing for its turntable which have certain advantages as being more economical to manufacture. In this embodiment of the invention the pedestal takes the form of a central standard or post 40 having spreading legs 41 radiating from its base to set upon the floor, or if preferred, to be carried on casters as shown in Fig. 1. The turntable 42 is provided with a central hub 43 from which the top-plate 44 is supported and braced by radial ribs 45. Driven into an axial bore in the hub 43, or otherwise suitably attached thereto, is a vertical shaft or spindle 46 fitted to turn in a bore 47 in the post or standard 40. The lower end of the spindle 46 is preferably formed with a beveled point 48 which pivots on the bottom of the bore 47, thereby providing a stepped bearing of anti-friction type as well known in the arts. The spindle 46 is prevented from rising up in its bore 47 by means of a set-screw 49 screwed through the side of the post 40 with its pointed end engaging an annular groove 50 on the spindle. Either of the above described forms of pedestal and bearing for the turntable provides a staunch and sturdy support for the cloth-frame which permits it to be easily revolved to unwind the goods therefrom.

In use my improved device holds a considerable quantity of fabric and protects the delicate finish of the goods from injury by contact. When desired the material may be further protected from dust and dampness by simply throwing a cover over the stand. My improved stand also provides for greater convenience in displaying the goods and delivering them for cutting up in lengths as required. To exhibit the fabric for inspection of its texture, finish and color a short length may be turned back by unpin-

ning its outer end and releasing it from the hooks on the ends of the frame 4; and to unwind a greater length it is only necessary to revolve the frame with its turntable, 5 while unhooking the selvages of the fabric to reel off any number of yards as required.

My improved display-stand besides being adapted for displaying fine goods such as pile-fabrics may also be used to good advantage with other materials; for instance, 10 to hold coated fabrics, imitation leather or the like, where it is desirable to protect the finish faces of the goods from contact.

I believe I am the first to provide a device 15 of this type having means for holding the fabric from surface contact, while allowing it to be conveniently unreeled for inspection or delivery in lengths as required; therefore I desire to claim the invention broadly as a 20 new and useful improvement in the art.

I claim and desire to secure by Letters Patent:

1. In a display-device for fabrics and the like, the combination with a reel-like cloth- 25 frame on which the fabric is wound, of a rotatable turntable, and means engageable with one end of the reel to clamp the latter to the turntable whereby the reel is rigidly supported thereon to rotate therewith to 30 adapt the fabric to be unreeled for display or delivery.

2. In a display-device for fabrics and the like, the combination with a reel-like cloth-frame on which the cloth is wound, of a 35 pedestal, a turntable rotatably mounted on the pedestal, and clamping-means on the turntable adapted to bind against the end-head of the cloth-frame to secure the latter rigidly against the top of the turntable to 40 adapt it for rotation to unreele the fabric.

3. In a display-device for fabrics and the like, the combination with a reel-like cloth-frame comprising metal end-members connected by a longitudinal stringer, of a pedestal, 45 a turntable rotatable on the pedestal, and clamping-members adjustable on the

turntable to engage across the edge of the end-members of the cloth-frame to clamp the latter to the turntable to attach the frame rigidly thereto whereby it may be 50 rotated to unreele the fabric.

4. In a display-device for fabrics or the like, the combination with a reel-like cloth-frame on which the fabric is wound, of a pedestal, a support for the cloth-frame rotatably mounted on the pedestal, clamping-hooks on the support adapted to engage the end of the cloth-frame, and means to adjust the hooks to different positions on the support to adapt them to cooperate with cloth- 55 frames of various sizes.

5. In a display-device for fabrics or the like, the combination with a reel-like cloth-frame on which the fabric is wound, of a pedestal, a support for the cloth-frame rotatably mounted on the pedestal, clamping-members adjustable radially of the support to adapt them to be set in position to cooperate with cloth-frames of various sizes, and means to tighten the clamping-members 60 65 against the cloth-frame to secure the latter rigidly with the support.

6. In a display-device for fabrics or the like, the combination with a reel-like cloth-frame having skeleton end-members, of a 70 support for the cloth-frame provided with slots, hooks slideable in the slots to adjust them into position to hook over the end-members of the cloth-frame, and means to clamp the hooks against the end-members 75 80 to secure the cloth-frame rigidly on the support.

7. In a display-device for fabrics or the like, the combination with a reel-like frame for holding the fabric, of a support for the 85 frame, clamping-means on the support for engaging with the end of the frame, and cam-levers for operating the clamping-means to bind the latter against the frame to fasten it rigidly to the support. 90

In testimony whereof I affix my signature.
HERBERT HORSFALL.
